United States Patent Office

Des. 185,932

Patented Aug. 18, 1959

185,932

CAP FOR A WRITING INSTRUMENT OR A SIMILAR ARTICLE

David Kahn, deceased, late of Englewood Cliffs, N.J., by Harry Yager, Englewood Cliffs, N.J., Julius M. Kahn,
Englewood, N.J., and Samuel Kahn, Englewood Cliffs,
N.J., executors, assignors to David Kahn, Inc., North
Bergen, N.J., a corporation of New Jersey

Application June 24, 1958, Serial No. 51,497

Term of patent 14 years

(Cl. D74—17)

FIG. 1

FIG. 2

FIG. 4

Fig. 1 is a front elevational view of a cap for a writing instrument or a similar article showing my new design; Fig. 2 is another elevational view thereof as it appears when turned 60°; Fig. 3 is a top plan view; and Fig. 4 is a side perspective view thereof.

What is claimed:

The ornamental design for a cap for a writing instrument or a similar article, substantially as shown.
